UNITED STATES PATENT OFFICE

1,998,261

VENEER WALL STRUCTURE

Otto A. Steuer, Los Angeles, Calif.

Application January 24, 1935, Serial No. 3,318

3 Claims. (Cl. 72—20)

This invention relates to structures by which bricks are used as a facing or veneer over other structures that form the base for the veneer or facing.

One of the objects of this invention is to provide a veneer wall structure of a rigidly and positively interconnected form.

Another object is to provide a connection between the facing or veneer and the base structure of a simple form that will not interfere with the customary laying of the facing, such as brick, and still assure a positive interconnection.

Another object is to provide a design or form of facing material that is especially adapted for such interconnection.

Other objects will appear from the following description and appended claims as well as from the accompanying drawing, in which—

Fig. 1 is a fragmentary top plan view of a layer of bricks as applied in form of a facing or veneer to a frame-structure base.

Fig. 2 is a vertical section on line 2—2 of Fig. 1.

Fig. 3 is a fragmentary vertical section on line 3—3 of Fig. 4 of a veneer applied to a concrete structure.

Fig. 4 is a horizontal section on line 4—4 of Fig. 3.

Fig. 5 is a perspective view of one form of connecting member.

Veneer facing is quite commonly used, but the facing material is mostly not sufficiently secured or held to the basic structure, which has been particularly demonstrated in earth-quake zones where such facing when not sufficiently secured has been some of the first matter shaken from the structures.

Under normal conditions, any reinforcement embedded in the mortar between bricks may be expected to serve as a sufficient anchor of a veneer facing by which to hold such facing to any other structure.

However, in earth-quake zones, mortar frequently becomes disturbed to such an extent that any anchor merely embedded in the mortar between the bricks will slip out of position so that any veneer becomes detached from the basic structure to which it serves as a facing or veneer.

As disclosed here, the facing material itself is designed and constructed so that a reinforcement can be properly applied; the reinforcement, for another thing, is designed of a special form, to assure a proper interengagement; and a special arrangement for a combined base-structure

and a veneer has been provided for, by which to accomplish the desired results.

A body in form of a brick or tile is commonly the principal part of a veneer or facing material. A brick or tile of a preferred form is illustrated in Figs. 1, 2, 3, and 4. The top surface of such a body 5 is provided with a central longitudinal groove 6 and crosswise grooves 7, in communication with the longitudinal groove, there being furthermore vertical passages extending from the intersections of the grooves to the opposite flat face of the body.

The width of such a body may be said to be substantially equal to half the length of the body, though more accurately it must be said that the width is a trifle smaller than half of the length, as may readily be understood from the corner arrangement, where the mortar 9 strikes the brick 5a just about in the middle, leaving equal portions of the whole length of the brick on both sides of this point so that the ends of two bricks could readily be placed against the side of such a brick 5a with a layer of mortar between the two bricks when so placed.

This proportioning brings the longitudinal groove 6 exactly in alignment with the cross groove 7, as can be seen plainly at the corner arrangement in Fig. 1, the cross grooves being substantially at the quarter point of the length of the brick, when considering the crosswise placing of some of the bricks with respect to lengthwise placed bricks.

A continuous passage is formed in this manner in the veneer throughout its length and following any corners, which is used to receive the reinforcement 10, as illustrated in Fig. 1, to become embedded below the top surface proper 11 of the brick, or within the outer contours of the brick, as indicated in Figs. 2 and 3, by which this reinforcement is not merely located in the mortar between the bricks.

To this reinforcement 10, a connection 12 is hooked, as illustrated in Figs. 2 and 3, the larger portion of this connection 12 being embedded or disposed in the cross groove 7 thereby being also below the top surface proper of the brick or within the outer contours of the brick, so that the side-wise pull or supporting hold for the veneer applies to a point within the outer contours of the brick body and not merely to a point within the mortar between the bricks.

No matter how much the mortar between the bricks become shattered under these conditions the connection for the veneer must remain intact

and cannot readily become dislocated to an extent that the veneer could possibly become dislocated when reinforced in this manner.

The opposite end of the connection is secured 5 to any base structure, such as a frame structure illustrated in Figs 1 and 2, or a concrete structure illustrated in Figs. 3 and 4.

With a frame structure, the connection is preferably bent upwardly, as indicated at 13 in Fig. 2, 10 to facilitate a spiking to the frame structure at a point above the top surface of the brick to which the reinforcement is applied as the veneer work proceeds upwardly on a structure.

A concrete structure, on the other hand, commonly requires that any attachments be embedded 15 in the concrete while this work is going on, the ends of the attachments commonly protruding from the surface of the finished concrete, to be bent as required for any matter that is to be applied to the surface of the concrete. The outwardly protruding ends of the connections 12a would therefore naturally have to be first lifted slightly to allow a placing of the veneer brick after 20 which the ends would have to be forced back downwardly to hook over the reinforcement 10 in the manner illustrated in Fig. 3.

The form for a connection illustrated in Fig. 5 is merely a modification to make it applicable as indicated at 12b in Fig. 1, to engage two bricks 25 simultaneously, the hook-ends 14 of any connection always hooking into the vertical passages of the bricks.

Having thus described my invention, I claim:—

1. In a combined base and veneer structure, a 35 veneer proper comprising individual bodies each of rectangular form having in its top surface a longitudinal groove and transverse grooves at about the quarter point of the length of the body and in communication with the longitudinal groove and

having furthermore vertical passages extending from the communications of the grooves downwardly, a base structure, and a reinforcement secured to the base structure and extending into the grooves of the bodies of the veneer below the top surface of the bodies. 5

2. In a combined base and veneer structure, a veneer proper comprising individual bodies, each of the bodies being of rectangular form and having in its top surface a longitudinal groove and transverse grooves in communication with the longitudinal groove with vertical passages extending from the communications of the grooves downwardly, a base structure, reinforcements extending throughout the longitudinal grooves of bodies placed endwise and through cross grooves wherever any of the bodies are placed endwise against the side of others, and connections having means engaging over the reinforcements and being disposed within grooves below the top surface 10 of the bodies and having other means connected to the base structure. 15

3. In a combined base and veneer structure, a veneer proper comprising individual bodies, each of the bodies being of rectangular form and having in its top surface a longitudinal groove and transverse grooves in communication with the longitudinal groove with vertical passages extending from the communications downwardly, a base structure, reinforcements extending throughout the longitudinal grooves of bodies placed endwise and through cross grooves wherever any of the bodies are placed endwise against the sides of others so that the cross grooves align with longitudinal grooves, and connections having means 20 engaging over the reinforcements and extending into the vertical passages and having other means connected to the base structure. 25

OTTO A. STEUER.
